CLAIM

The ornamental design for a personnel location recording display board, as shown and described.

DESCRIPTION

FIG. 1 is a perspective view of the personnel location recording display board embodying the design of the present invention;

FIG. 2 is a front elevational view thereof, the rear being a mirror image of the front shown in FIG. 2;

FIG. 3 is a top plan view thereof;

FIG. 4 is a bottom view thereof;

FIG. 5 is an end elevational view thereof; and,

FIG. 6 is an end elevational view thereof.

FIG. 1

FIG. 2

FIG. 3

FIG. 4

FIG. 5

FIG. 6
